UNITED STATES PATENT OFFICE.

JAMES CROSLEY, OF DRIFTWOOD, PENNSYLVANIA, ASSIGNOR TO HIMSELF AND DAVID D. ANGELL, OF SAME PLACE.

DESIGN FOR A HOE.

SPECIFICATION forming part of Design No. 14,092, dated July 17, 1883.

Application filed May 19, 1883. Term of patent 7 years.

To all whom it may concern:

Be it known that I, JAMES CROSLEY, of Driftwood, in the county of Cameron and State of Pennsylvania, have invented a new and useful Improvement in a Design for a Hoe, of which the following is a full, clear, and exact description.

My invention relates to a design for double-bladed hoes; and its novelty consists in the form of parts hereinafter described and claimed.

Reference is to be had to the accompanying drawings, forming a part of this specification, in which similar letters of reference indicate corresponding parts in both the figures.

Figure 1 is a view in perspective of a double-bladed hoe, showing the handle only in part, with my improved design as applied to the connected blades; and Fig. 2 is a section on the line *x x* through one of the blades.

A is the shank of the hoe, and *B* its blades, arranged side by side on opposite sides of the shank. These blades, when viewed from their front or back, present reverse convex inner 25 and outer side edges, *b c*, meeting in points *d* below where the inner and outer side edges, if extended, would intersect, and said blades, where they are united above with the shank, present upper and lower curved or arched configurations, *e f*—that is, at their junction with each other and the shank. Each blade, too, is 30 of a gentle hollow or concave form on its face

s in direction of its length, and of a reversely-tapering form in direction of its width through its body part, presenting opposite inclined surfaces, *g h*, on its inner face, with its greatest thickness near its inside edge, but vanishing away toward the point *d*. 35

Having thus fully described my invention, I claim as new and desire to secure by Letters 40 Patent—

1. The design for the form or configuration of a double-bladed hoe, which consists in the inner and outer side edges of the combined blades, made of reverse convex forms, meeting 45 in points below, said inner edges extended upward to form an arched or curved connection between the blades where they join the shank, as herein shown and described.

2. The design for the form of a double-bladed hoe, which consists in the outer side edges of the combined blades, corresponding closely to convex arcs of circles, meeting the sides of the shank in reverse curves, each inner edge being an internally-convex curve 50 along its lower portion, meeting the out edge curve at a point below, the said inner curves reversing as they ascend and joining each other in an elliptical arch, as shown. 55

JAMES CROSLEY.
